CASTING SHOT

James E. Hatfield, Shaker Heights, Ohio, assignor
to Grant Storage Battery Company, Minneapolis, Minn., a corporation of Minnesota

Application September 22, 1942, Serial No. 459,240

1 Claim. (CL 22—153)

This invention relates to the making of shot, and has for its principal object to provide a method and apparatus by which lead shot may be cast very economically, rapidly, and accurately.

An important feature of the present invention is the manner in which the shot are cast. According to the present invention, a quantity of shot is cast in a mold in a sheet or multiple sheet with the shot cavities extending horizontally and vertically. Perfect shot are formed by reason of the manner in which the mold cavities are vented. The cavities are arranged in horizontal rows which are filled from the bottom to the top, it being a feature of the invention that the cavities are connected not only horizontally but also vertically by small passages or channels so that each shot cavity is well vented with the result that the lead shot which is cast therein is perfectly formed, and when the casting is completed each shot is connected to the adjacent shot by narrow connecting portions.

Not only is each mold cavity vented vertically as well as horizontally, which facilitates the casting of the shot in a sheet or group, but in view of the facility with which the metal flows into and upwardly from each cavity, the temperature of the molten metal can be less than would otherwise be the case. After the casting has been made, water is sprayed on the casting to more quickly congeal the metal, and then, by means of a gang punch, each shot is severed from the adjoining shot, leaving four burrs where the connecting portions were located. Next the shot are subjected to infra-red rays or other means for rapid drying to prevent the formation of an oxide on the metal and are then placed in a tumbling barrel where the burrs are pressed into the shot in the tumbling operation.

The invention may be further summarized as consisting in certain novel details of construction and in certain details of the method described in the specification and set forth in the appended claim.

Referring now to the drawings,

Fig. 1 is a perspective view of a two-part mold in which the casting is made;

Fig. 2 is a face view of one of the mold members on a larger scale than shown in Fig. 1, looking in the direction of the line 2—2 of Fig. 1;

Fig. 3 shows a view of the casting which is produced in the mold;

Fig. 4 is a sectional view through a gang punch

by which the shot are severed from the casting;

Fig. 5 is a view taken along the line 5—5 of Fig. 4, showing a face view of the male gang punch;

Fig. 6 is a view taken along the line 6—6 of Fig. 4, showing the female gang punch;

Fig. 7 is an enlarged sectional view showing the action of the male and female punching members;

Fig. 8 is a view of one of the shot with the burrs thereon following the punching operation; and

Fig. 9 is a view of one of the shot after the tumbling operation.

Referring now to the drawings, Fig. 1 represents the two complemental members 10 and 11 of the mold in which the shot casting is made. Inasmuch as the illustrated casting is to be made in the form of a twin sheet, the mold is provided with three pouring gates 12, 13 and 14. One of the mold members has a series of ejecting pins 15 projecting from the rear side thereof. At the top of the mold, between the gates 12 and 13, and between the gates 13 and 14 there are provided, respectively, narrow vent passageways 16 and 17.

By reference to Fig. 2 it will be noted that extending from each gate 12, 13 and 14 are, respectively, vertical passageways 18, 19 and 20, the middle passageway 19 being preferably somewhat wider than the two end passageways 18 and 20. Additionally, the mold is provided with a lower horizontal passageway 21 and an upper horizontal passageway 22 joining the three vertical passageways.

Extending from the passageway 18 to the passageway 19 and from the passageway 19 to the passageway 20 are series of superposed equally spaced horizontal rows of shot cavities 23, the cavities of each horizontal row being connected by horizontal channels 24. Similarly, the cavities of each horizontal row are connected by vertical channels 25 to the cavities above and below. The cavities of the lowermost row are connected to the lower passageway 21 by vertical channels 26 while the cavities of the uppermost horizontal row are connected by channels 27 to the upper passageway 22. In a similar fashion the vertical rows of cavities next to the vertical passageways 18, 19, and 20 are connected to these passageways by channels 28. It will be understood, of course, that the above described cavities, passageways, and channels are formed

in the adjacent faces of both mold members 10 and 11 so that when the mold members are closed the cavities, passageways, and channels of one mold member are in registering complementary relation with those of the other mold member to form the completed mold.

It will be seen that with a mold formed as described, when the molten lead is poured into the pouring gates 12, 13, and 14, it will flow down the vertical passageways 18, 19, and 20, and it will fill successively the horizontal rows of cavities from the bottommost to the topmost. This progressive filling of the cavities from the bottom to the top of the mold facilitates the escape of air from the cavities and enables the cavities to be filled completely and rapidly with metal.

It might be here stated that to facilitate the locating of the casting produced by the mold in the gang punch press, one of the mold members is provided with a pair of pins 29 which extend across the uppermost channel 22 so as to form openings in the casting.

In Fig. 3 I have shown a casting which is produced in accordance with the present invention. It will be noted that this casting includes three sprues 30, a framework consisting of three vertical lead bars 31, 32, and 33, a lower lead bar 34 joining the vertical bars and an upper horizontal bar 35 which likewise joins the three vertical bars 31, 32, and 33, two flashes 36 and 37 where the vent passages 16 and 17 occur between the gates and two groups of framed lead shot 38, one located in the frame formed by the lead bars 31, 32, 34, and 35 and the other located in the frame formed by the bars 32, 33, 34 and 35.

It will be seen that the shot are spaced equal distances from one another throughout each framed mass and that they are connected both horizontally and vertically by connecting portions 39. The mold cavities are completely filled and the shot are of practically uniform size throughout due to the venting feature by which each shot cavity of each horizontal row is vented vertically to the shot cavity above and also connected to the shot cavity below. This would not be possible if the horizontal rows were independent of each other and the shot cavities thereof were not all connected to the cavities above and below, but some of the cavities, particularly those at or adjacent the center of the horizontal rows would be imperfectly filled.

It will be noted by reference to Figs. 2 and 3 that the molten lead passes down the vertical passageways 18, 19 and 20 to the bottom thereof and gradually rises in these passageways as the molten lead flows horizontally into the shot cavities which are fed not only from the vertical passageways but by way of the vertical channels 25 into the shot cavities of the horizontal row above. Thus the mold is filled from the bottom up, eventually forming the upper bar 35 of the framework and the flashes 36 and 37. When the operator sees the metal rise in the openings 16 and 17, he knows that he has poured enough molten lead into the gates.

It might be stated in passing that the vertical bars 18, 19 and 20 add strength to the casting so as to facilitate the handling of the casting after it has been ejected from the mold.

As was previously stated, the facility with which the shot are cast permits a lower temperature of the molten metal than would be the case if a longer time was required for the casting operation. Thus there is a saving in the gas

or other fuel required to heat the lead melting pot.

With my improved venting there is also effected a saving of lead, for the weight of the lead in the grille of cast shot is practically equal to the weight of the lead in the framework plus the sprues and flashes. If the lead flowed into the shot cavities and were vented solely from end to end rather than upwardly, a much heavier volume of lead would be required to get the metal into the cavities, particularly the middle cavities of each horizontal row, and even then, due to the lack of provision for venting the cavities independently of the inlets and outlets at opposite ends of the horizontal rows, the middle cavities might not be completely filled.

When the mold is opened and the casting is removed therefrom, the casting will be found to contain two openings 40 where the pins 29 occur.

As soon as the casting is removed from the mold, water is sprayed on it so as to quickly congeal the metal and then the casting is placed in a gang punch having a series of punches 41 spaced in accordance with the spacing of the shot 38 in each double framework or grille, which punches are carried by a holder 42 which is actuated in any suitable manner and which is slidable in a frame 43. Cooperating with the gang punches 41 and equal in number and spacing thereto are a series of openings 44 located in a stationary die plate 45 supported by a member 46 of the gang punch. The lead casting is accurately located in the gang punch by the holes 40 which are cast therein, which holes receive a pair of pins 40a, Fig. 6, of the lower plate 45 of the gang punch.

With this arrangement by one downward stroke of the holder 42 all the lead shot are punched out of the double framework in the manner best shown in Fig. 7. As shown in Fig. 4, they drop down into a cavity having a sloping bottom 47 with an outlet opening 48. The framework, including the sprues 30 and flashes 36 and 37, is returned to the melting pot. This procedure frees the shot 38 from the double framework, except that there are four small burrs 49 on each shot where the shot was severed from the connecting portions 39. In practice, the sloping bottom 47 is a wire screen through which the lead connections fall but which will not pass the shot. After the gang punch has operated and the male member has returned to its highest position, an air blast is used to remove the lead connections from the top of the female die member. Some of these, during the action of the air blast, may fall through the female openings in the die and then pass through the screen into a suitable receptacle.

Inasmuch as the shot are formed from pure lead which very readily oxidizes, it is desirable that oxidation be prevented, particularly for certain uses of the shot. Accordingly, a quick drying of the shot is desirable, and immediately after the shot are punched from the framework, they are subjected to rays from infra-red lamps.

Next the shot are placed in a tumbling chamber and are tumbled until the burrs are completely driven into the shot, thus leaving a perfectly smooth exterior surface thereon as shown at 50 in Fig. 9. While the shot are of practically uniform diameter, they can, if necessary be screened or sorted by first passing them over a screen through which the undersized shot will

pass, and then over a screen through which the shot of the required diameter will pass.

Thus it will be seen that there are numerous advantages which flow from the use of shot cavities vented horizontally and vertically.

While I have shown the preferred construction and have described the preferred steps of the method, I do not desire to be confined to the precise details shown, but aim in my claim to cover all modifications which do not involve a departure from the spirit and scope of my invention.

Having thus described my invention, I claim:

A mold for making shot having pouring gates

at the top and a series of upright feeding channels leading to the bottom of the mold with air venting means between the pouring gates, and a series of shot cavities arranged in horizontal rows between the upright feeding channels, each row of cavities being directly connected with the upright feeding channels and each cavity being directly connected to the cavities above and below it, whereby the molten metal, on being poured into the gates, gradually fills the upright feeding channels and successively flows into the horizontal rows of cavities, each cavity being vented upwardly.

JAMES E. HATFIELD.
